SMOKING CHARACTER FIGURE

George H. Messmore, New York, N. Y.

Application March 18, 1950, Serial No. 150,444

1 Claim. (Cl. 46—9)

1

This invention relates to new and useful improvements in smoking character figures.

Prior smoking character figures are unnatural in that the smoke is discharged in a steady stream or in an interrupted stream, or merely in puffs. There is therefore no resemblance to an actual smoker in which drawing and puffing and exhaling and curling of the smoke actually occurs.

The dominating object of this invention resides in the construction of a smoking character figure in which the timing of the smoking is synchronized with the motion of the figure and in which proper amounts of smoke are discharged both from the mouth and the pipe, or other article being smoked.

In accordance with this invention the new smoking character figure includes a movable character figure having a mouth and a movable arm holding a smoking pipe, cigar or cigarette or other article being smoked, which engages said mouth and which is moved from said mouth upon motion of said movable arm. The invention proposes the use of two separate smoke producers connected respectively with said pipe and with said mouth. Drive means is provided for periodically moving said movable arm through a cycle of movements which includes moving the arm towards and from the mouth. A separate bellows is provided for each of the smoke producers and an operating cam works each of said bellows for operating the bellows during said cycles to issue smoke from said pipe as if said figure were drawing and puffing when the pipe is in its mouth, and when said arm moves from said mouth to issue smoke in curls at short spaced intervals from said pipe and also to issue smoke from said mouth as if exhaling. It is proposed that said cams be driven by the drive means which works the movable arm so that the timing of the motions of the figure and the issuance of the smoke are synchronized. It is pointed out that the cams control the action of the bellows, and with this construction proper amounts of smoke may be issued from the mouth and from the pipe in correct amounts during the operation of a complete cycle.

Another object of this invention resides in the particular construction of the smoke producers. It is proposed to so construct said smoke producers that there is always a sufficient quantity of smoke which issues from the producers only upon the operation of a draft of air produced by the bellows.

Another object of the invention is the construction of a smoking character figure as described which is simple and durable and which may be manufactured and sold at a reasonable cost.

For further comprehension of the invention,

10 and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a fragmentary side elevational view of a smoking character figure constructed in accordance with this invention.

Fig. 2 is a fragmentary enlarged vertical sectional view taken on the line 2—2 of Fig. 1.

Fig. 3 is an enlarged side elevational view of one of the smoke producers.

Fig. 4 is an end view of the smoke producer illustrated in Fig. 3 to which schematic wiring has been applied to show its operation.

The smoking character figure, in accordance with this invention, includes a movable character figure 10 having a mouth 11 and a movable arm 12 holding a smoking pipe 13 or other smoking item, which engages said mouth 11 and is moved from said mouth 11 upon motion of said movable arm 12. The details of this movable character figure will not be given in this specification as it forms no part of this invention. However, it should be realized that the movable character figure may have numerous moving parts, such as its head, eyes, other arm, etc.

20 A smoke producer 15 is provided with a smoke exit tube 16 which is connected with the mouth 11. This smoke producer 15 preferably is located in the head of the figure adjacent said mouth 11. Another and similar, but separate, smoke producer 17 is located adjacent the pipe 13 and is provided with a smoke exit tube 18 which connects with the pipe 13. A bellows 19 is connected with the smoke producer 15 by a tube 20 which connects with the air inlet tube 21 of the smoke producer 15. Another bellows 22 is connected by a tube 23 with the air inlet tube 24 of the smoke producer 17. These bellows 19 and 22 are mounted within the body of the character figure 10. The tubes 20 and 23

25 are flexible and extend through the body and into the head, and through the body and into the arm 12, respectively. Because the tubes 20 and 23 are flexible the head and arm 12 may readily move. The movable arm 12 is pivotally supported at the shoulder by a pintle 25. Drive means is associated with said movable arm 12 for moving it through a cycle of movements which includes moving said arm towards and away from said mouth 11 so that the pipe 13 is engaged into and removed from the mouth. This drive means includes a radial arm 26 within the body of the figure 10 and connected with the arm 12 so as to move the arm 12 upon motion thereof. This radial arm 26 is connected by a rod 27 with an-

30 35 40 45 50 55 60 65 70 75 80 85 90 95

other rod 28 which is pivotally mounted at the end 29 upon a support 30. The arm 28 is provided with a cam follower 31 engaging a cam groove 32 of a cam 33 secured to a rotative shaft 34. This shaft 34 is connected with a gear reduction unit 35 which in turn is connected with the electric motor 36. When the motor 36 rotates the cam 33, the arm 28 will be oscillated upwards and downwards and this motion will be transmitted to the arms 26 and 27 to correspondingly move the movable arm 12.

Each of the bellows 19 and 22 is driven by a separate cam. More particularly, the bellows 19 is provided with an operator arm 38 which connects with an arm 39 pivotally mounted at the end 40 upon a standard 41. The arm 39 is provided with a follower 42 engaging a cam groove 43 of a cam 44 secured to the shaft 34. When the shaft 34 is driven, the cam 44 will rotate and the follower 42 will oscillate the arms 39 and 38 so as to pump the bellows 19 to issue smoke from the mouth 11 in desired quantities with the periods synchronized with the motion of the arm 12 of the movable character figure 10.

The bellows 22 is operated by an arm 46 which connects with an arm 47 pivotally supported at the end 48 upon a standard 49. The arm 47 is provided with a follower 50 which engages a cam groove 51 in a cam 52 secured to the shaft 34. When the cam 52 rotates, the arms 47 and 46 will be oscillated to work the bellows 22 so as to issue smoke from the pipe 13 in desired amounts, the periods being synchronized with the operation of the arm 12 of the movable character figure 10.

Each of the smoke producers 15 and 17 are of identical construction. The smoke producer 15 will be described and shown in detail in Figs. 3 and 4. It comprises a housing 60 containing a supply of mineral oil 61. The housing 60 has a removable cover 62 which may be removed when mineral oil is added. The housing 60 is provided with a smoke exit tube 16 and with an air inlet tube 21. These tubes 16 and 21 are arranged on opposite sides of the housing so that air may be blown through the housing from the air inlet tube 21 to the smoke tube 16. A heating coil 68 is mounted within the housing 60 and extends into the mineral oil 61. This heating coil 68 includes an electric coil 63 connected with the secondary 64 of a transformer 65 having a primary winding 66.

The operation of the smoking character figure may be understood from the following:

Current is supplied to the transformer 65 so that the heating coil 68 provides sufficient heat to convert the mineral oil 61 into smoke within the housing 60. The electric motor 36 drives the shaft 34. The cam 33 on the shaft 34 oscillates the arms 28, 27 and 26 so as to move the movable arm 12 which moves towards the mouth 11 so as to engage the pipe 13 in the mouth 11 and then moves away from the mouth 11 to disengage the pipe from the mouth. The exact motion of the movable arm 12 will be controlled by the formation of the cam groove 32.

The cams 44 and 52 which are all driven by the shaft 34 simultaneously work the bellows 19 and 22. More specifically, the cam 44 works the bellows 19 which controls the discharge of air through the smoke producer 15. The cam 52 works the bellows 22 which controls the discharge of air through the smoke producer 17. The shape of the cam grooves 43 and 51 of the cams 44 and

52 are such that smoke issues from the mouth 11 and pipe 13 to simulate natural smoking. This simulation may be as follows. When the pipe 13 is in the mouth 11 smoke is discharged from the pipe 13 in interrupted puffs to simulate drawing and puffing. When the arm 12 moves away from the mouth 11 smoke is simultaneously discharged through the mouth 11 by the smoke producer 15 to simulate exhaling, and simultaneously the smoke producer 17 is operated so as to cause smoke to curl at intervals from the pipe 13.

It should be particularly noted that because the smoke producers 15 and 17 are driven by the same drive means which drives the movable arm 12, the issuance of smoke from the mouth 11 and pipe 13 will be synchronized with the motion of the figure 10. It should also be realized that because smoke issuing from the mouth 11 and the pipe 13 are controlled by the separate bellows 19 and 22 operated by separate cams 44 and 52, the quantity and timing of the smoke may be accurately controlled so as to simulate a person smoking.

25 While I have illustrated and described the preferred embodiment of my invention, it is to be understood that I do not limit myself to the precise construction herein disclosed and the right is reserved to all changes coming within the scope of the invention as defined in the appended claim.

Having thus described my invention, what I claim as new and desire to secure by United States Letters Patent is:

35 A smoking character figure, comprising a movable character figure having a mouth and an arm which holds a smoking pipe and which is movable in one direction to bring the smoking pipe to the mouth and which is movable in the opposite direction to move the smoking pipe away from the mouth, reciprocating drive means connected to said arm and causing it to move intermittently toward and away from the mouth and thereby causing the smoking pipe to move intermittently toward and away from the mouth, two separate smoke producers connected respectively with said smoking pipe and with said mouth, a separate bellows connected with each of said smoke producers for blowing smoke through said smoking pipe and said mouth, a pair of driven cams and a pair of cam followers engaging said cams, said cam followers being connected to the bellows for actuating the same in response to the cam action thereon, said cams being contoured for irregular cam action upon the cam followers to cause irregular actuation of the bellows in stroke and timing in order to blow smoke through the smoking pipe and mouth at corresponding time intervals and in varying quantities, said cams being synchronized with said reciprocating drive means to synchronize the blowing of the smoke with the movement of the arm.

GEORGE H. MESSMORE.
